UNITED STATES PATENT OFFICE.

ISHAM U. MALPHURS, OF LACROSSE, FLORIDA.

COMBINED SPRING-BED AND FIRE-ESCAPE.

SPECIFICATION forming part of Letters Patent No. 670,798, dated March 26, 1901.

Application filed March 6, 1900. Serial No. 7,568. (No model.)

To all whom it may concern:

Be it known that I, ISHAM U. MALPHURS, a citizen of the United States, residing at La-
crosse, in the county of Alachua and State of
Florida, have invented certain new and use-
ful Improvements in a Combined Spring Bed-
Bottom and Fire-Escape, of which the follow-
ing is a specification.

My invention relates to a combined spring
bed-bottom and fire-escape, the object being
to provide a spring bed-bottom which may be
readily unfolded for use as a fire-escape ladder,
so constructed as to be manufactured at
small expense, and capable of being quickly
and easily folded and unfolded.

The construction of the improvement will
be fully described hereinafter and defined in
the appended claim, in connection with the
accompanying drawings, which form a part
of this specification.

In the drawings, Figure 1 is a front eleva-
tion of the invention in its unfolded position
suspended from a window-sill ready for use
as a fire-escape. Fig. 2 is a side elevation
of the same, the window-sill being shown in
section. Fig. 3 is a plan view of the two sec-
tions in their folded position disconnected and
placed side by side to form a spring bed-bot-
tom. Fig. 4 is a side elevation of one section
of the device in its folded position, and Fig.
5 is a view in perspective of a supplemental
ladder-section adapted for use when necessary
for attachment to the bed-bottom sections to
lengthen the ladder.

I preferably employ two foldable sections,
(although more than two sections may of
course be used, if desired,) and as both sec-
tions are the same in construction a detail
description of one will suffice for both.

Each section of the device comprises a plu-
rality of short ladders loosely secured together
by pivoted links. The number of ladders
composing a section of the bed-bottom is of
course not material and may vary with the
requirements of use. In the drawings each
section comprises five ladders, the sides of
which are designated by the numerals 1, 2, 3,
4, and 5, respectively. 1, 3, and 5 are long
ladders and 2 and 4 are short ladders.

The numeral 6 designates the rounds of the
ladders.

The upper ends of the sides of the ladder 1

are provided with hooks 7, adapted to engage
eyes 8, projecting from the window-sill. The
lower ends of the sides of the upper ladder 55
are connected by links 9 with the upper end
of the sides 2 of the next adjacent ladder by
pivot-rivets 10 and pivot-pins 10^a, provided by
the projecting ends of each alternate pair of
rounds 6^a, and the lower ends of the sides 2 60
are connected by links 9 with the next sec-
tion, and so on.

To the upper round of the ladder 1 and
lower round of the ladder 5 are secured two
coil-springs 11 of the conical form shown. To 65
each of the rounds of the ladders 2 and 4 are
secured two coil-springs, (designated, respec-
tively, 12 and 13,) and the springs 12 on one
round are connected by integral connecting-
rods 14 with the springs 13 of the adjacent 70
round, providing twin coil-springs. The cen-
tral ladder-section is unprovided with springs
to facilitate the folding of the device to the
position shown in Figs. 3 and 4.

Fig. 3 shows the two bed-sections folded and 75
arranged side by side to form the bed, the
links 9, connecting the sections 1, 2, and 3,
being folded in opposite directions under the
section 2, and the links connecting the sec-
tions 3, 4, and 5 being similarly folded under 80
the sides of the section 4.

In Fig. 5 is shown a supplemental ladder-
section comprising sides 15 and rounds 16,
the ends of the rounds being provided with
snap-hooks 17, adapted to be attached to hooks 85
or loops on the ends of the bed-sections to
lengthen the ladder, as will be readily un-
derstood.

The utility and operation of the invention
will be readily understood. When the two lad- 90
der-sections are in their folded position and
placed side by side they form a serviceable
spring bed-bottom, and when the sections are
unfolded and connected together they form
a ladder of sufficient length to reach from the 95
window to the ground in all ordinary build-
ings. If additional length is required, one
or more of the supplemental sections (shown
in Fig. 5) may be used in addition to the sec-
tions carrying the springs.

I claim—

A combined spring bed-bottom and fire-es-
cape, comprising long ladders each having
rounds, short ladders alternating with the

long ladders each having rounds extending therethrough to provide pivot-pins, links connected at one end to the pivot-pins, pivot-rivets connecting the other ends of the links to the long ladders, and coil-springs secured to the outer rounds of the outer long ladders, and to the rounds of the short ladders, the links permitting the short ladders to be super-

posed over the adjacent ends of the long ladders.

In testimony whereof I affix my signature in presence of two witnesses.

ISHAM U. MALPHURS.
